DESIGN FOR A DRY CLEANING MACHINE CABINET

Joseph Novotny, Fort Wayne, Ind., assignor to
S. F. Bowser & Company, Incorporated, Fort Wayne, Ind., a corporation of Indiana

Application April 14, 1939, Serial No. 84,292

Term of patent 7 years

To all whom it may concern:

Be it known that I, Joseph Novotny, a citizen of the United States, residing at Fort Wayne, Allen County, Indiana, have invented a new, original, and ornamental Design for Dry Cleaning Machine Cabinets, of which the following is a specification, reference being had to the accompanying drawing, forming a part thereof.

The figure is a perspective view of a dry cleaning machine cabinet embodying my new design.

The other end of the cabinet is like the end shown in the figure.

I claim:

The ornamental design for a dry cleaning machine cabinet, as shown and described.

JOSEPH NOVOTNY.
